UNITED STATES PATENT OFFICE.

CHARLES T. PAYE, OF NORTH ATTLEBORO, MASSACHUSETTS, ASSIGNOR TO PAYE & BAKER MANUFACTURING COMPANY, OF NORTH ATTLEBORO, MASSACHUSETTS, A CORPORATION OF MASSACHUSETTS.

DESIGN FOR A JEWELRY PIN, CHARM, FOB, PENDANT, CUFF-BUTTON, RING, OR SIMILAR ARTICLE.

49,591.

Specification for Design.

Patented Aug. 29, 1916.

Application filed June 6, 1916. Serial No. 102,097. Term of patent 3½ years.

To all whom it may concern:

Be it known that I, CHARLES T. PAYE, a citizen of the United States, residing at North Attleboro, in the county of Bristol, State of Massachusetts, have invented a new, original, and ornamental Design for Jewelry Pins, Charms, Fobs, Pendants, Cuff-Buttons, Rings, or Similar Articles, of which the following is a specification, reference be-

ing had to the accompanying drawing, forming a part thereof.

The figure is a plan view of a jewelry pin illustrating my new design.

I claim:—

The ornamental design for a jewelry pin, charm, fob, pendant, cuff button, ring or similar article as shown.

CHARLES T. PAYE.
